E. H. STEPP

ORE SEPARATOR

Filed Nov. 22, 1926

UNITED STATES PATENT OFFICE.

EDDIE H. STEPP, OF KNOXVILLE, TENNESSEE.

ORE SEPARATOR.

Application filed November 22, 1926. Serial No. 150,069.

The invention relates to ore separators.

The object of the invention is to provide an ore separator which will effectively separate the valuable mineral, such as flour gold, from the entering concentrate mass.

The invention will first be described and specifically pointed out in the claims.

This object I accomplish by the construction shown in the accompanying drawings, in which

Figure 1 is a side elevation of the separator with the casing broken away;

Fig. 2 is a central vertical section thereof;

Fig. 3 is a horizontal section on line 3—3 of Fig. 2;

Fig. 4 is a similar view on line 4—4 of Fig. 2;

Fig. 5 is a section on line 5—5 of Fig. 2, and

Fig. 6 is a section on line 6—6 of Fig. 2.

The base 1, of the machine, is a box-like structure provided in its bottom with a step bearing 2 and having on its top a collar or extension containing a two part bearing collar 8 extending down through an opening in the top of the case 1 having supporting flanges 9, 9' and securing bolts 9, 9'. The upper edge of the collar 8, at its four corners, is provided with lugs or ears 10, between which is bolted the lower end of the separator bowl 11; said lower end having attaching lugs or ears 12 through which and the lugs or ears 10 are passed the horizontal securing bolts 13 as shown in Fig. 4.

The bowl 11, is elliptical in shape and formed in two separable sections having vertically disposed flanges 14, secured in close contact by the hand bolts 15.

The upper contracted closed end of the bowl has a central aperture through which depends the downwardly projecting end 16 of the pipe 17 which supplies the bowl with the water and mineral bearing concentrate. The inner walls of the two part bowl 11 are provided with ring-like plates or troughs 18, which are also in sections corresponding to the bowl sections. These plates or troughs 18 lie in parallel horizontal planes and contain amalgam 19, which is held stationary thereon.

A vertical cylinder 20, open at its upper end, is mounted within the bowl 11 and has a depending vertical shaft 21 extending down through the lower open end of the bowl 11 and through the bearing 8, with its lower end stepped in the bearing 2. The bottom of this

cylinder also carries amalgam. The shaft 21 may be driven by a pulley 22 and belt 23 or by any other suitable means, such as a motor of any desired type capable of rotating the shaft at a high speed.

The interior of the rotary cylinder 20 is provided with helical ribs or vanes 24 and its exterior is also provided with similar helical ribs or vanes 25. The shaft 21 is provided below the bearing 8 with a stop collar 26 held by a set screw 27. At opposite sides of the bearing 8, the top of the base 1 is provided with outlet openings 27', see Fig. 5, and below these openings is placed an offtake chute or spout 28 to carry the waste material away. This outlet chute or spout 28 is also coated with amalgam to save the last particles of the valuable mineral content of the concentrate.

The operation is as follows: the depending pipe 16, delivers the water and concentrate down close to the bottom of the centrifugal cylinder, which is rotated by any suitable means, at a high speed. The helical ribs 24 on the interior of the cylinder 20 cause the liquid concentrate to be carried up and over the upper edge thereof where the down flow will be interrupted by the outer helical ribs 25. The centrifugal action will cause these ribs 25 to throw the whirling body of concentrate lying between the cylinder 20 and the inner wall of the bowl 11 outwardly into contact with the stationary bodies of amalgam 19 to which the gold or other metal to be separated will adhere. Furthermore the fin or rib 25 on the exterior of the cylinder operates on the material overflowing each trough except the lowest, to project the material against the bowl wall over succeeding troughs. This action will be kept up as long as there is any mineral to be saved; the centrifugal action and ribs 25 acting to prevent inflow through pipe 16 and holding the whirling water and concentrate against running out through the outlet. That is to say, when the cylinder 20 is rotated at a sufficiently high speed, its external helical rib 25 will check the flow from the intake pipe 16 and little or none will escape through the outlet 27 and this may be kept up long enough for every particle of the gold or material to be saved to be thrown against the amalgam and be saved.

This is especially desirable in recovering flour gold which floats off in the water of ordinary riffles where mere agitation does no good.

Various changes may be made without departing from the spirit and scope of my invention.

What I claim is:

- 5 1. A centrifugal ore separator, comprising a bowl having an amalgam retaining trough on its inner wall, and an inner rotary member provided with means on its exterior for lifting the body of concentrate and water to
  - 10 retard the downflow thereof and simultaneously throwing it outwardly to bring the valuable heavier mineral content into contact with the said amalgam surface.
  - 15 2. A centrifugal ore separator, comprising a bowl having an amalgam retaining trough on its inner wall, an inlet for the fluid concentrate at the upper end of the bowl and an outlet for the waste at the lower end thereof and an inner rotary member mounted con-
  - 20 centrically within the bowl, means on the exterior of said rotary member for simultaneously exerting a lifting force to retard the downflow and an outwardly acting centrifugal force on the concentrate to hold the concentrate in place and throw the heavier mineral content into contact with said amalgamated surface; and means for rotating the rotary member at a speed high enough to cause the rotary member to function as de-
  - 25 scribed.
  - 30 3. A centrifugal ore separator, comprising an outer bowl having amalgam retaining means on its inner wall, an inner centrifugal cylinder open at its upper end and provided with interior and exterior helical ribs or fins,
  - 35
- an intake pipe extending down into said cylinder, and means for rotating said centrifugal cylinder at a high speed to hold up the body of water in the outer bowl and concentrate and throw the material to be recovered 40 outwardly against the amalgam.
4. The combination with an outer bowl provided on its inner wall with a series of amalgamating plates or troughs, and a rotating cylinder open at its upper end to receive 45 the water and concentrate and provided on its inner and outer sides with helical fins or ribs, whereby by rotating the cylinder a centrifugal force is set up by the outer fin or rib to overcome the gravitational force of the water 50 and concentrates carrying the mineral particles to be recovered and to throw said particles outwardly into contact with the amalgam.
5. A centrifugal ore separator comprising 55 a base, a vertically divided bowl removably secured at its lower end to the top of the base and having an outlet leading from the lower end of the bowl and amalgam retaining means on its interior; a vertical cylinder 60 within the bowl, open at the upper end and having a shaft depending from its lower end and mounted in bearings on the base, said cylinder having helical ribs or fins on its inner and outer sides, an intake or supply pipe for the water and concentrate extending down through the top of the bowl into the said cylinder.

In testimony whereof, I affix my signature.
EDDIE H: STEPP.
